SAMUEL B. REMINGTON, OF ADRIAN, MICHIGAN.

AIR-DAMPER RELEASE FOR FURNACES.

1,110,577.

Specification of Letters Patent. Patented Sept. 15, 1914.

Application filed December 11, 1912. Serial No. 736,058.

To all whom it may concern:

Be it known that I, SAMUEL B. REMINGTON, a citizen of the United States, residing at Adrian, in the county of Lenawee, State 5 of Michigan, have invented certain new and useful Improvements in Air-Damper Release for Furnaces; and I do declare the following to be a full, clear, and exact description of the invention, such as will enable 10 others skilled in the art to which it appertains to make and use the same, reference being had to the accompanying drawings, and to the characters of reference marked thereon, which form a part of this specification.

15 This invention relates to an air damper release for furnaces of the steam boiler type, and consists in the construction and arrangement of parts hereinafter more fully set forth and pointed out particularly in 20 the claims.

The object of the invention is to provide simple and efficient means whereby the air damper which controls the draft opening of a furnace may be automatically closed 25 whenever steam in the boiler reaches a predetermined pressure, provision being made for enabling the air damper to be opened irrespective of the boiler pressure.

The above object is attained by the structure illustrated in the accompanying drawings, in which:

Figure 1 is a general view showing the application of my invention to a steam heater of the Gurney type. Fig. 2 is a front elevation of the adjustable automatic release. Fig. 3 is a vertical section as on line 3—3 of Fig. 2. Fig. 4 is a perspective view of the pivotally mounted spring restrained detent to which the chain of the air damper is 40 adapted to be connected.

Referring to the drawings by the characters of reference marked thereon, 1 designates a steam heater having the usual ash door 2 in which is located an air damper 3 which is hinged at 4 to close by gravity. Communicating with the steam space of the heater is a pipe 5, which, at its upper end, communicates with the case 6 of a diaphragm, said diaphragm being in turn supported by a standard 7 mounted on the boiler casing, or said diaphragm may be otherwise suitably supported. Projecting from the diaphragm case 6 is a bracket 8 to which a lever 9 is fulcrumed, as shown at 55 10. The bearing stem 11 passes through the

diaphragm case and engages the under side of said lever. Also mounted upon the diaphragm case are guides 12 between which the lever reciprocates. Connected at its lower end to the air damper 3 is a chain 13, 60 the upper end of which is connected to the projecting end of the lever 9. Also connected to and leading upwardly from said lever is a chain 14, whose upper end is provided with a ring 15. Located at a suitable point in the house or building, preferably upon the main floor, is a case 16. Fulcrumed at the lower end of said case, between the sides thereof upon a transverse pin 17, is a detent 18, having an outwardly projecting finger 70 19. The rear side of the detent 18 has a straight face 20 (see Fig. 4), which, when the parts are in their normal position, is adapted to engage a rubber buffer 21 which is mounted in the rear wall of the case. 75 Projecting from the upper portion of the detent is a lug 22 having an eye 23 therein. Engaging in the eye of said lug is a terminal member 24 of a relatively stiff coil spring 25 which is suspended vertically 80 within the case from the hook 26 of an adjusting screw 27 mounted to move vertically through the upper end 28 of the case, and receiving on its upper end a thumb nut 29.

When there is no pressure in the steam 85 space of the heater, or when said pressure is low, the air damper 3 may be opened by drawing upwardly upon the chain 14 and may be held open by engaging the ring 15 at the end of said chain over the projecting 90 finger 19 of the detent. The parts will remain in this position until the fire, which is caused to burn more briskly by the opening of the air damper, shall have raised the pressure in the boiler to a predetermined 95 point, or to a point sufficient to overcome the resistance of the spring 25, when the diaphragm will be actuated to cause its stem 11 to engage the lever 9 and move it upon its fulcrum against the resisting action 100 of said spring to draw the finger 19 of the detent downwardly until the ring 15 slips therefrom, permitting the lever 9 to assume the position shown by dotted lines in Fig. 1, 105 and allowing the air damper to close. Whenever the air damper shall have been closed by the operation just described it will remain closed until it is again opened by the manual operation of drawing upwardly on the chain 14 and engaging the ring 15 over 110

the projecting finger 19 of the detent. In each case after the damper shall have been opened it will remain open until sufficient pressure is created in the boiler to move the diaphragm valve and actuate the lever 9 to disengage the ring 15 of the chain 14 from the finger of the detent.

Whenever the detent is actuated by a downward draft upon the chain 14 through the actuation of the lever 9, the ring 15 will slip from said detent when it shall have been drawn downwardly to the position shown by dotted lines in Fig. 3. After the ring 15 slips from engagement with the finger of the detent the retracting power of the spring 25 will return the detent to its normal position with its rear face in engagement with the buffer 21, said buffer serving to deaden the noise incident to the forcible return of the detent by the spring 25.

It will be understood that by means of the wing nut 29 the tension on the spring 25 may be so regulated as to cause an actuation of the lever 9 to automatically release the air damper whenever the pressure in the heater shall have reached a predetermined point. By this arrangement overheating the building is avoided, as the air damper will automatically close when the boiler pressure reaches a certain point, and will remain closed until it is manually opened, thereby enabling a low heat to be carried when and as long as desired. In the back of the case 16 are apertures 30 (see Fig. 3) adapted for

the reception of screws which may be employed for securing the case in position.

Having thus fully set forth my invention, what I claim as new, and desire to secure by Letters Patent, is:

1. In an automatic release for air dampers, a pressure actuated diaphragm, a pivoted lever connected to said diaphragm to be actuated thereby, a pivotally mounted detent, a spring for restraining said detent, means for varying the tension of said spring, means for detachably connecting said detent to said lever to permit a disengagement of said parts as the lever moves upon its pivot in one direction, an air damper, and means connecting said air damper to said lever.

2. In an automatic release for air dampers, a pivotally mounted detent, a spring detachably connected to said detent, an adjusting screw in engagement with said spring, a buffer to cushion the recoil of the detent, a pivoted lever, means for detachably connecting said lever to said detent, a diaphragm connected to said lever to impart movement thereto, a hinged air damper, and means connecting said damper to said lever.

In testimony whereof, I sign this specification in the presence of two witnesses.

SAMUEL B. REMINGTON.
